A. E. BLOCK,
ARCH SUPPORT,
APPLICATION FILED OCT. 9, 1915.

Patented Aug. 15, 1916.

INVENTOR:—
ALEXANDER E. BLOCK.
BY *James L. Hopkins*,
ATTORNEY.

UNITED STATES PATENT OFFICE.

ALEXANDER E. BLOCK, OF ST. LOUIS, MISSOURI.

ARCH-SUPPORT.

1,194,812.

Specification of Letters Patent. Patented Aug. 15, 1916.

Application filed October 9, 1915. Serial No. 55,095.

To all whom it may concern:

Be it known that I, ALEXANDER E. BLOCK, a citizen of the United States, residing in the city of St. Louis and State of Missouri, 5 have invented certain new and useful Improvements in Arch-Supports, of which the following is a specification, reference being had therein to the accompanying drawing.

My invention relates to improvements in 10 arch supports and has for its object to provide a support for the longitudinal and anterior metatarsal arches of the human foot, which may be used as a support for either or both of said arches.

15 In the drawings—Figure 1 is a bottom plan view of a support embodying my invention. Fig. 2 is a transverse sectional view of the same taken on the line 2—2 of Fig. 1. Fig. 3 is a sectional view of a fragment of the same taken on the line 3—3 of Fig. 1. Fig. 4 is a plan view of one of the inserts employed in the device of my invention. Fig. 5 is a transverse sectional view of said insert.

25 As shown in the drawings I employ a flexible insole 6 adapted to be seated in the shoe of the wearer and extending from the heel of the shoe to a point beneath the anterior metatarsal arch of the wearer's foot.

30 Upon the lower face of the insole 6 I provide the tubular pockets 7 and 8, 7 being longitudinally mounted in alinement with the longitudinal arch of the wearer, and 8 being transversely mounted in alinement 35 with his anterior metatarsal arch. These pockets 7 and 8 are of flexible material, and are detachably secured to the lower face of the insole 6 by any suitable means, that illustrated in the drawings being the lines of 40 stitching 9; the purpose being to permit either of the pockets 7 or 8 to be readily ripped or otherwise detached and removed from the insole 6 when only one pocket is required in the support and treatment of 45 the wearer's foot.

Within the pocket 7 one or more of the inserts 10 may be mounted at any point desired; and within the pocket 8 one or more of the inserts 11 may similarly be mounted.

50 To secure said inserts 10 and 11 against ac-

cidental displacement I provide the pockets 7 and 8 with apertures 12—12 arranged at their edges opposite each other, and adapted to receive the flexible ears 13—13 with which the inserts 10 and 11 are provided on their 55 outer edges.

By the described means I am enabled to support either arch of the foot at any desired point, and to shift the point of support when desired. I am also enabled to 60 furnish to the trade in a single article of manufacture a support for both arches, which the dealer can instantly convert into a support for one arch alone by detaching and removing that one of the pockets (7 or 65 8) which is not needed by his customer; the dealer buying but one line of the various sizes (men's, women's and children's) of the present device, instead of having to purchase the said several sizes of two lines of 70 supports, one line adapted to the treatment of the anterior metatarsal arch only, and the other to the treatment of the longitudinal arch only.

By the term "pocket" as used in this description and in the claims is meant a receptacle for inserts, having substantially parallel sides and being open at either or both of its ends, and mounted on the lower 75 face of an insole.

80 The inserts may be of any desired shape or outline, or of any suitable material.

Having thus described my invention, what I claim as new, and desire to have secured to me by the grant of Letters Patent, is—

85 1. In an arch support, an insole; a pocket mounted on the lower face of the insole and having apertures along its length; and an insert arranged to fit within said pocket and having means to engage with said apertures. 90

2. An arch support comprising an insole provided on its lower face with a detachable pocket extending longitudinally of said insole and a detachable pocket extending transversely of said insole; and inserts arranged to be adjustably mounted along the length of said pockets. 95

3. An arch support comprising an insole provided on its lower face with a pocket extending longitudinally of said insole and a 100

pocket extending transversely of said insole; and inserts arranged to be adjustably mounted along the length of said pockets.

4. An arch support comprising an insole provided on its lower face with a pocket extending longitudinally of said insole and a pocket extending transversely of said insole;

inserts arranged to be adjustably mounted along the length of said pockets; and means for locking said inserts within said pockets 10 against accidental displacement.

In testimony whereof I hereunto affix my signature.

ALEXANDER E. BLOCK.
